UNITED STATES PATENT OFFICE.

BYERS W. KADEL, OF BALTIMORE, MARYLAND.

DOOR MECHANISM FOR RAILWAY CARS.

Application filed January 23, 1925. Serial No. 4,193.

My invention relates to door mechanism for railway cars, and has as one of its principal objects to provide improved means for closing and supporting the car doors. A more specific object of the invention is to provide an improved arrangement of door latching members whereby the door may be automatically supported in an approximately closed position and thereafter forced to fully closed position and locked. Another object is to provide a door supporting mechanism involving a movable door supporting member carried by the car body and adapted to engage a cooperating door supporting member movably mounted upon the door. With these general and other more specific objects in view, the invention consists of the construction, combination and arrangement of parts herein disclosed and claimed.

20 In the accompanying drawings which show a preferred form of the invention,—

Figure 1 is a fragmentary side elevational view of the hopper portion of a railway car of the well known twin hopper type, showing a mechanism embodying the invention applied thereto.

Figure 2 is a view similar to Fig. 1, but illustrating the door as supported in partly closed position instead of in fully closed position.

30 Figure 3 is a horizontal sectional view of the mechanism, taken substantially on the line 3—3, Fig. 1.

In the drawings, the side of the car or the hopper end sheet is indicated by the numeral 1. The door 2 controlling the discharge opening of the hopper may be hinged along its upper edge to the car body in any usual or convenient manner, such hinge connections being well known to those familiar with the art of car construction. The car side 1 is preferably flanged outwardly along the side of the hopper discharge opening to form a seat 3 for the door and to provide a sealing flange 4. The door plate is also preferably flanged as at 5, not only to stiffen the edge of the door but to afford an outstanding marginal flange cooperating with the flange 4 of the car body to constitute sealing means preventing the loss of lading.

Rigidly secured to the outer face of the door, as by means of rivets 6, is a transversely extending door stiffening member 7 which may also serve as a door connector or door spreader in case the door is made in two parts for cooperating with hopper discharge

openings on opposite sides of the car center sill construction.

In the illustrated embodiment of the invention, which is deemed to be preferable, the stiffening member 7 is in the form of a channel iron whose web extends outwardly and one of whose flanges abuts against the door plate. The channel is notched at its outer end, as at 8, so as to clear the sealing flanges 4 and 5, the end portion of said channel thus being enabled to project outwardly somewhat beyond the side of the car and the said sealing flanges when the door is in closed position. It is advantageous to dispose the channel iron 7 so that its flanges are turned downward, as the back of the channel is thus most conveniently positioned for the attachment of a movable door supporting member.

Pivotedly mounted on the outer face of the car side 1 is a movable door supporting member adapted to engage the outer end of the stiffening member 7 to support the door in partly closed position. The door supporting member carried by the car body is preferably in the form of a hook or latch 9 pivotally mounted upon a bracket 10 located back of the shoulder or seat 3 at the discharge end of the hopper, the said bracket preferably being so constructed as to cause the latch 9 to be positioned just outwardly of the sealing flange 4 and to swing in a plane parallel with the car side. A rivet 11 with a washer 12 may be employed to attach the bracket 10 to the car and also to secure the latch in assembled relation to the pivot bracket. In order to maintain the latch 9 within its normal plane of swing it is advantageous to provide a guide or support which overlaps the outer face of the latch. This guide 13 is preferably formed as a suitably offset bar which is attached to the flange 4 of the car side sheet by means of rivets 14. Sidewise movement of the latch 9 is thus prevented, as it will be restrained between the flange 4 and the said guide 13.

Car doors of the character herein disclosed may readily be swung by hand to a position in which they are nearly closed; but because of warping and deformation due to the rough usage to which railway cars are subjected in service, very much greater force must be applied to the doors to completely close them. The present invention is designed to facilitate the closing of car doors by providing efficient means for forcing the

door to closed position after it has been man-
ually swung nearly shut. To enable the piv-
oted latch 9 to temporarily support the door
at the end of its preliminary closing move-
ment, said latch is provided with an inclined
approach portion 15 which contacts with a
portion of the door as the latter moves to-
ward closed position, thus causing the said
latch to swing upward. A continuation of
the closing movement of the door allows the
lowermost point 16 of the supporting ledge
of the latch to pass beyond the outermost
edge of the channel door stiffener 7, thereby
permitting said latch to drop and engage
the outermost flange of the door stiffener 7,
as illustrated in Fig. 2. In this position of
the parts the door will be supported in part-
ly closed position.

Mounted upon the upper face of the outer
end portion of the member 7 is an eccentric
or cam 17 which is pivotally attached to the
web of said channel member 7 by means of a
pivot rivet 18 and washers 19. The rivet
18 is so positioned with respect to the di-
rection of the rivet 11 upon which the hook
9 is pivotally mounted that the cam 17 and
the said hook preferably swing in planes at
substantially a right angle to each other.
Before swinging the door to partly closed
position by hand, the cam 17 should be rotat-
ed to a position enabling the point 16 of the
latch 9 carried by the car body to drop clear
of the periphery of the cam. When the latch
9 has assumed a position, as shown in Fig.
2, in which it serves to support the door in
partly closed position, rotation of the cam 17
in the proper direction causes its eccentric
periphery to engage the ledge of the latch at
somewhat above its lower end 16. Con-
tinued rotation of the cam 17 causes it to
wedge against the door supporting hook 9
so as to force the door inwardly toward the
car body to completely closed position. The
portion 20 of the ledge of the latch 9 pref-
erably is a greater distance from the pivot
point of said latch than is the lowermost
portion 16 of the ledge, thus causing the por-
tion 20 to be undercut with respect to the pre-
liminary latching point 16 of the hook.
When the cam 17 has been forcibly rotated
while in engagement with the portion 20 of
the hook 9 so as to force the door to com-
pletely closed position, the offset portion 16
of the ledge assumes a position beneath the
cam 17 and the latter thus operates to pre-
vent the latch 9 from swinging upwardly
and releasing the door. The cam 17 accord-
ingly serves not only as a means for forcing
the door shut but also as a means for locking
the hook 9 against accidental release from its
door supporting position when the door is
finally closed. It also is to be noted that the
hook 9 and cam 17 constitute cooperating
door supporting members for sustaining the
load upon the door which are movably

mounted upon the car body and door re-
spectively. It will be observed also that the
cam 17 in effect forms a movable or adjust-
able support for the seat carried by the door
for engagement with the hook 9.

70

The cam 17 may be provided with a socket
21 into which a removable bar 22 may be in-
serted for forcibly rotating the cam. When
it is desired to release the door the cam is
rotated until the portion 16 of the pivoted
hook 9 is able to be swung upwardly out of
engagement with the periphery of the cam.

75

While I have described a preferred em-
bodiment of my invention other embodiments
thereof are contemplated within the scope
of the appended claims.

80

I claim:

1. A car body having a door adapted to
be supported in different positions of clo-
sure, a latch pivotally mounted on the car
body adapted to engage a relatively immov-
able portion of the door to maintain the lat-
ter in partly closed position, and means car-
ried by the door movable into and out of en-
gagement with the latch to support the door
in fully closed and partly closed position
respectively.

85

2. A railway car having a door, a pivoted
latch carried by the car body adapted to en-
gage a relatively immovable portion of the
door to maintain the latter in partly closed
position, and a pivoted cam carried by the
door and adapted to engage said latch, said
cam being adapted to be moved so as to force
the door shut.

90

3. A railway car having a door, a stiffen-
ing member for the door, a pivoted latch
mounted upon the car body and adapted to
engage said door stiffening member, and
movable means carried by the door stiffening
member and adapted to be interposed be-
tween said door and latch, said means being
adapted to be moved so as to effect a clos-
ing movement of said door and being adapt-
ed to lock said latch in door supporting po-
sition.

100

4. A railway car having a door, a stiffen-
ing member for the door, a pivoted latch
mounted upon the side of the car and adapt-
ed to engage the door stiffening member to
support the latter in partly closed position,
and rotatable means interposed between said
latch and the door whereby the door may be
forced toward closed position.

105

5. A railway car having a door, a door
supporting latch pivoted upon the side of
the car and adapted to swing into support-
ing engagement with the door, and means
on the door forming a seat for said latch,
said means involving a member movable with
respect to the door and adapted when in en-
gagement with said latch to move in a plane
substantially at right angles to the plane
of operation of said latch.

110

6. A railway car having a door, a door

115

supporting latch pivoted upon the side of the car and adapted to swing into supporting engagement with the door, and means carried by said door forming a seat for said latch, said means involving a member movable with respect to the door and adapted when in engagement with said latch to move in a plane forming an angle with the plane of operation of said latch.

10. 7. A railway car having a door, a stiffening member carried thereby, a latch pivotally mounted on the car body, and means pivotally mounted on one end of the stiffening member adapted to engage the latch to support the door in closed position, the pivotal axis of said means extending at an angle to the pivotal axis of the latch.

15. 8. A railway car having a door, a pivoted latch mounted on the car body, pivoted means carried by the door adapted to engage the latch to support the door in closed position, the pivotal axis of said means forming an angle with the pivotal axis of the latch, and means on the latch to prevent disengagement of the latter from the said pivoted means when the door is in fully closed position.

20. 9. A railway car having a door, a latch pivotally mounted on the car body, and rotatable means carried by the door cooperating with the latch to support the door in

closed position, the axis of rotation of said means being substantially parallel to the plane of operation of the latch, said means being adapted to be rotated into engagement with the latch to lock the same in door supporting position and also being adapted to be rotated out of engagement with the latch to permit the latch to be swung into door releasing position.

25. 10. A car body having a door, a latch pivotally mounted on the car body, and a rotatable cam carried by the door adapted to engage the latch to support the door in closed position, said cam having a portion fashioned to receive a removable bar for rotating the cam, the bar being adapted when in operable engagement with said cam to move in a plane forming an angle with the plane of operation of said latch.

30. 11. A car body having a door, a latch pivotally mounted on the car body, and a rotatable cam carried by the door adapted to engage the latch to support the door in closed position, said cam having a portion fashioned to receive a removable bar for rotating the cam, the bar being adapted when in operable engagement with the cam to extend in a direction substantially transverse of the car.

In testimony whereof I affix my signature. 60
